CLAIM

The ornamental design for an insect trap device, as shown and described.

DESCRIPTION

FIG. 1 is a top-down view of a first embodiment of the insect trap device;

FIG. 2 is a bottom view of the first embodiment of the insect trap device;

FIG. 3 a top perspective view of the first embodiment of the insect trap device;

FIG. 4 is a side view of the first embodiment of the insect trap device;

FIG. 5 is a side view of the first embodiment of the insect trap device, as rotated from the side view shown in FIG. 4; FIG. 6 is a second top perspective view of the first embodiment of the insect trap device, featuring a dotted line shown for reference with respect to FIG. 7;

FIG. 7 is an interior side view of the first embodiment of the insect trap device, taken along the dotted line as shown in FIG. 6;

FIG. 8 is a top-down view of a second embodiment of the insect trap device;

FIG. 9 is a bottom view of the second embodiment of the insect trap device;

FIG. 10 a top perspective view of the second embodiment of the insect trap device;

FIG. 11 is a side view of the second embodiment of the insect trap device;

FIG. 12 is a side view of the second embodiment of the insect trap device, as rotated from the side view shown in FIG. 11;

FIG. 13 is a second top perspective view of the second embodiment of the insect trap device, featuring a dotted line shown for reference with respect to FIG. 14; and,

FIG. 14 is an interior side view of the second embodiment of the insect trap device, taken along the dotted line as shown in FIG. 15.

(Continued)

The dotted lines shown in FIG. 6 and FIG. 13 are shown for purposes of illustration, and do not constitute part of the claimed design.
